GLASS DISH

Paul Schneeloch, Brooklyn, N. Y.

Application April 22, 1950, Serial No. 9,428

Term of patent 14 years

(Cl. D36—2)

To all whom it may concern:

Be it known that I, Paul Schneeloch, a citizen of the United States, residing at Brooklyn, New York, in the county of Kings, and State of New York, have invented a new, original, and ornamental Design for a Glass Dish, of which the following is a specification, reference being had to the accompanying drawing, forming part thereof. In the drawing:

Fig. 1 is a bottom plan view of a glass dish, showing my new design;

Fig. 2 is a side elevational view of the same;

Fig. 3 is a top plan view of the dish; and

Fig. 4 is a vertical section on the line 4—4 of Fig. 3.

I claim:

The ornamental design for a glass dish, as shown.

PAUL SCHNEELOCH.
